MANUFACTURE OF GASOLENE.

1,131,309.

Specification of Letters Patent.

Patented Mar. 9, 1915.

Application filed May 2, 1913. Serial No. 764,982.

To all whom it may concern:

Be it known that we, RAYMOND F. BACON, BENJAMIN T. BROOKS, and CLINTON W. CLARK, citizens of the United States, residing at Pittsburgh, Allegheny county, State of Pennsylvania, have invented certain new and useful Improvements in the Manufacture of Gasolene; and we do hereby declare the following to be a full, clear, and exact 10 description of the invention, such as will enable others skilled in the art to which it appertains to make and use the same.

The invention relates to the treatment of mineral oils whose boiling point is 250° C. 15 and upward, for the production therefrom of a mixture of hydrocarbons principally of the C_nH_{n+2} series, boiling below 200° C., said product being intended particularly for use as a fuel for internal combustion engines.

The mineral oils from which the product is obtained are petroleum hydrocarbons, as, for instance, American and Mexican petroleums. The operation, as hereinafter described, is conducted at a pressure of from 60 lbs. to 300 lbs. per square inch, and at a temperature of from 350° C. to 500° C. Under these conditions of pressure and temperature, small particles of tar and coke are 30 continuously produced in the body of oil. These particles, settling out of the mass and dropping down upon the hot bottom of the usual horizontal or vertical still tend to agglomerate and adhere to said bottom with 35 great tenacity and are difficult of subsequent removal. Moreover, they not only diminish the conduction of heat from the furnace gases to the oil within the still, but it is found that they increase the danger of explosion by increasing the tendency of the 40 still bottom to burn through.

The present invention is designed to avoid the difficulty just referred to, by conducting the operation under such condition that the 45 particles of tar and coke produced in the mass will tend to move out of the cracking zone of the still and deposit themselves in a part of the apparatus separate therefrom.

Another feature of the invention is based 50 upon the discovery that while the production of the desired product depends upon the maintenance of the high temperature and the high pressure hereinbefore described, the rate of production is a function

of the area of heating surface employed and, 55 for most purposes, may be regarded as represented by the ratio of the heating surface to the volume of the oil within the heating space. Accordingly, it is found that the maximum yields, in a given unit of time, 60 from a given volume of oil heated, are obtained when the ratio of the heating surface to the volume is correspondingly large. In practice, we have employed with entirely 65 satisfactory results, tubes of an internal diameter as large as 19 inches (corresponding to a ratio expressed in comparable units, of internal periphery to internal capacity of 1:4.7; this numerical ratio being derived when the inch is taken as the unit of measurement). We do not recommend the employment of tubes of materially larger diameter because of the rapidly decreasing yield in gasolene beyond that point.

In establishing the desired relationship 75 between the heating surface for the body of oil and the volume of the oil undergoing cracking and distillation thereby, there is likewise embodied in the same construction and procedure, the feature hereinbefore referred to, of permitting the particles of tar and coke that are formed during the operation to move out and deposit themselves in a part of the apparatus separate from the heated surfaces which effect the cracking of 80 the oil. Thus, in the preferred practice of the invention, the still is constructed in such a manner that its heating zone is upright and is a portion of a tube, of small diameter with respect to its length. The tube is supplied with the oil in any suitable manner, as, for instance, by a pump discharging into its upper portion. At its lower end, the tube leads into a receptacle for the collection of the tar and coke particles. The arrangement is preferably such that the receptacle in which the tar and coke are received is entirely below the heating zone of the tube, so that the particles of tar and coke will fall freely through the oil column into the collecting space below in substantially their entirety. Whatever particles of tar and coke chance to be deposited upon the upright walls of the heating zone, their amount is relatively small, so that the cleaning of the 105 tube to remove such accretions is not frequently required.

It is further characteristic of the present

invention that the danger of explosions is materially lessened and, in fact, is rendered almost impossible, at the pressures employed, because of the much larger resistivity to pressure incident to the employment of small tubes as compared with the employment of a single large still, either of the horizontal or vertical type.

In the accompanying drawing, Figure 1 represents, partly in section, and partly in elevation, a form of apparatus suitable for the practice of the invention; Fig. 2 represents a partial view of another modification of the invention, showing its applicability 15 to advantage in multiple units.

Similar letters of reference indicate similar parts in both the views.

Referring particularly to Fig. 1, A indicates a storage tank for the petroleum hydrocarbons to be treated, and B indicates a pump for delivering a regulated supply therefrom to the still through the conduit a.

In Fig. 1, is shown a single unit consisting of a tube b, of steel or other suitable metal and whose length is preferably 20 ft. or more, when the internal diameter of the tube is 6 inches. The heating zone of the tube is intermediate of its ends and, in the form shown in Fig. 1, consists of a fire brick chamber C having suitable air inlets, as d, and a suitable exit opening, as e, for the products of combustion. The chamber C may receive its heat from any convenient source, as, for instance, a series of annular 25 gas burners f, supplied with a mixture of air and gas from the gas conduit D whose branches g terminate in injecting tips, as shown, and which draw in with them a suitable supply of air through the bell h opening into the atmosphere. At its lower end, the tube b communicates with a tar and coke receiving receptacle E, located below, outside of the heating zone.

At the beginning of the operation, the charge of oil to be cracked and distilled is established up to the level indicated in Fig. 1, that is to say, at a level slightly higher than the internal wall of the top of the heating chamber C. This level of the body of oil is kept practically constant, by means of the pump B, which supplies oil to the interior of the tube as the cracking and distillation proceed. Accordingly, the products of combustion do not come into direct contact with any portions of the tube not occupied by the liquid oil, and consequently, the danger of destructive distillation of any portion of the vapors by coming into contact with overheated portions of the tube 55 above the zone of liquid oil is minimized and the formation of an adhering layer of coke upon such portion of the walls of the tube is avoided.

The free portion of the tube extends above the furnace setting, as shown, for a distance

of say 3 feet. The vapors pass, by means of the pipe i, to the condenser coil J, contained within the cooling receptacle F. The condenser coil is provided at its end with a valve k and discharges into the receptacle 70 G. The uncondensed gases and vapors from the receptacle G pass by the pipe l into a body of oil contained within the receptacle H, wherein such particles of oil as are contained in the residual gases are trapped and 75 recovered. The surplus gases and vapors pass off through the conduit m. At the bottom of the receptacle E, a pipe n conveys the residual tar and coke to a receiving tank I, the flow being under the control of 80 a regulable valve s.

From the foregoing description of the purposes of the invention, and of the construction of the apparatus shown in Fig. 1, the mode of operation will be fully apparent. The receptacle E and the tube B, are filled to the level indicated, and the annular burners f are ignited. The temperature rises to the range hereinbefore referred to, that is to say 350° C. to 500° C., and the 85 pressure is likewise permitted to rise, by shutting off the valve K either wholly or partially, as the case may be, until the pressure gage t indicates the pressure desired, that is to say, a pressure within the range 90 of 60 lbs. to 300 lbs. per square inch. Thus, at 100 lbs. pressure, about 75-90% of the entire body of oil may be distilled with the production of a resultant condensate containing a large percentage of material boiling below 200° C., the temperature being about 95 425° C. About 35% of the condensate obtained at this pressure and temperature has a boiling point below 150°, and almost all of this product is of the C_nH_{2n+2} 100 series, appropriate for use for the ordinary purposes of gasoline, as, for instance, for use as fuel for internal combustion engines and would usually be rated commercially as gasoline. In general, it is preferred, as indicated, to operate at a pressure of 100 lbs. for the reason that the relative portion of material boiling below 150° C. is greater when the operation is 105 conducted at 100 lbs. pressure than when conducted at the lower pressure of 60 lbs. per square inch. The higher pressures up to 300 lbs. are employed when it is desired to still further increase the relative proportion of material in the condensate boiling 110 below 150° C., but at the higher pressures there is progressively more coke and gas formed and hence a lower percentage of 115 total condensate is obtained.

During the cracking and distilling operation, any particles of tar and coke that may be formed in the body of the distilling oil tend to fall through the vertical heating zone, by gravity, into the receiving space 120 of the chamber E. A relatively small 125

amount of tar and coke will, in the course of time, build up upon the vertical walls of the tube B within the heating zone, but these accumulations are relatively unimportant 5 and slow of formation, and, should they become excessive, may be readily removed by the use of any ordinary boiler flue cleaner, or the like. The petroleum residue containing the coke accumulating in the receptacle

10 E is drawn off from time to time through the pipe n into the receiver I.

In the form of the invention indicated in Fig. 2, there is shown a series of individual tubes b, having at the bottom a common 15 header E' corresponding in function and location to the receptacle E of Fig. 1. The tubes b are located in a heating flue C' supplied with a flow of hot products of combustion from any suitable source, 20 so as to heat the tubes to the high temperatures hereinbefore referred to, the header E' being located in a cooler space below the heating flue. a' indicates a supply pipe communicating with the interior 25 of the several tubes b, so as to furnish oil thereto. So also, the pipe i' constitutes the exit pipe for the vapors. The supply pipe a' and the exit pipe n' from the header E' are connected by the cross-connecting 30 pipe v having a valve x and containing the liquid level gage w, so that the operator will be able to know at any time the oil level within the several tubes b. The mode of 35 operation of this modification will be clear from what has been said in regard to the mode of operation of the form of the apparatus shown in Fig. 1, and need not be further elaborated.

Having thus described the invention, what 40 is claimed is:

1. The method of producing from petroleum oils which have a boiling point of 250° C. and upward, a mixture of hydrocarbons boiling below 200° C., which consists in subjecting the petroleum oils treated 45 to a combined cracking and distilling opera-

tion at a temperature within the range of 350° C. to 500° C., and at a pressure within the range of 60 lbs. to 300 lbs. per square inch, progressively removing from the heating zone the particles of tar and coke produced therein and depositing them out of contact with the walls of said heating zone; substantially as described. 50

2. The method of producing from petroleum oils which have a boiling point of 250° C. and upward, a mixture of hydrocarbons boiling below 200° C., which consists in subjecting an upright column of the oil to a combined cracking and distilling 60 operation at a temperature within the range of 350° C. to 500° C. and at a pressure within the range of 60 lbs. to 300 lbs. per square inch, and permitting particles of tar and coke produced in the upright column of oil 65 to fall by gravity from the upright column into a receiving space below said column; substantially as described. 55

3. The method of producing from petroleum oils which have a boiling point of 250° C. and upward, a mixture of hydrocarbons boiling below 200° C., which consists in subjecting the petroleum oils treated to a combined cracking and distilling operation at a temperature within the range of 350° C. to 500° C., and at a pressure within the range of 60 lbs. to 300 lbs. per square 70 inch, and establishing during the cracking and distilling operation, a ratio (expressed in comparable units) of cracking heating 75 surface to the volume of oil not substantially less than 1:4.7, this ratio being derived when the inch is employed as the unit of measurement; substantially as described. 80

In testimony whereof we affix our signatures, in presence of two witnesses.

DISCLAIMER

1,131,309.—*Raymond F. Bacon, Benjamin T. Brooks, and Clinton W. Clark, Pittsburgh, Pa. MANUFACTURE OF GASOLENE.* Patent dated March 9, 1915. Disclaimer filed August 25, 1930, by the assignee, *Gulf Refining Company*.

Therefore disclaims from the scope or meaning of claims 1, 2, and 3 of said Patent 1,131,309 any method of producing a mixture of hydrocarbons which includes subjecting petroleum oils to a pressure within a range below 100 pounds per square inch.
